UNITED STATES PATENT OFFICE.

FRANCIS W. D'OLIER, OF MOORESTOWN, NEW JERSEY.

PENCIL.

Application filed October 26, 1921. Serial No. 510,492.

To all whom it may concern:

Be it known that I, FRANCIS W. D'OLIER, a citizen of the United States, residing at Moorestown, in the county of Burlington 5 and State of New Jersey, have invented certain new and useful Improvements in Pencils, of which the following is a specification.

This invention relates to pencils and pertains particularly to magazine pencils and 10 to pencils for carrying extra lead.

One of the objects of the invention is to provide a compact simple device which will be durable and easily operated, and at the same time inexpensive to manufacture.

15 The features of the invention provide for the utmost simplicity in the arrangement and construction of parts, thus reducing the chance of breakage and binding of the parts to a minimum. The relative simplicity of 20 the parts makes it possible to dispense with the need for special manufacturing machines.

The features of the invention provide numerous advantages over the known forms 25 of pencils. In the present construction, whenever the front cap or tip is off for re-loading, the amount of reserved lead in the magazine may be seen because such extra leads project up beyond the barrel end and 30 are finally covered by the tip when the latter is attached to the barrel.

Another important advantage results from the peculiar spring feed feature which permits a cushioned effect, and prevents the 35 breaking of lead, and reduces to a minimum the tiring effect experienced by the writer after using a pencil for a long time in continuous writing.

Another feature is the use of a transparent 40 cover for the pencil and the particular way in which both end covers co-operate with the sleeve to complete the structure.

The particular configuration and relative position of the parts is set forth in the following 45 specification and claims, and illustrated in the accompanying drawing in which:

Fig. 1 is an enlarged view of a section taken centrally and longitudinally through 50 the pencil;

Fig. 2 is a side view of the unitary combined actuated screw and plunger, as removed from the pencil;

Fig. 3 represents an end view of the barrel 55 of the pencil, showing the actuated screw

and plunger in position within the barrel and the plunger within the central tube; and

Fig. 4 represents an end view of the actuating end piece, with the eraser removed, and illustrating the position in which the extreme rear end of the actuating spring screw member is secured to the actuating end piece.

Referring in detail to the drawing, 1 indicates the barrel of a pencil of the type described enlarged considerably in order to more clearly show the relative positions of the parts. 1^a indicates the rear end of the barrel and 1^b indicates the front end of the barrel, and these ends are provided with the respective threaded outer portions 1^c and 1^d. Screw threaded to the end 1^a is a rear end cap 2 having screw threads 2^a on the inner surface thereof engaging the threads 1^c of the barrel. The rear face of the cap 2 is indicated at 2^b, and centrally through this rear face is an opening 2^c, the purpose of which will be described. The opposite end of the cap 2 provides an annular shoulder or flange surface 2^d having a thickness the same as the wall of the cap. The front end is provided with a screw threaded fastening cap 3 which has a rear portion 3^a with threads adapted to engage the threads 1^d of the barrel. Tapering forwardly from the portion 3^a, the inner walls of the tip are indicated at 3^b and this tapered portion extends into a more sharply inclined part indicated at 3^c. The rear end of the cap is provided with the square cut shoulder or annular flange surface indicated at 3^d corresponding to the shoulder 2^d of the rear end cap. The extreme tip of the pencil is indicated at 3^e and a restricted bore for providing a tight sliding fit for the lead is indicated at 3^f.

Between the point 3^e and the bore 3^f, there is provided a cylindrical portion having the walls 3^g which provides a loose sliding fit for the central guide tube as will be described. Between the walls 3^g and immediately adjacent the entrance to the bore 3^f is the annular inclined surface 3^h against which the central tube is adapted to rest in order to position the tube centrally and bring the bore of the tube into alignment with the bore 3^f.

A transparent sleeve 4 of celluloid or other suitable material is loosely fitted over the length of the barrel 1 and held in position by the flange surfaces 2^d and 3^d. Preferably

the cylinder 4 has walls of the same thickness as the width of the flanges, so that the assembled pencil may provide a smooth exterior. Between the barrel 1 and the cylinder 4 there may be inserted suitable advertising material for display through the cylinder 4, or designs for artistic effect or advertising material may be carved on the outer surface of the barrel 1 and thus made visible through the cylinder 4 although protected from actual wear by the outer transparent covering.

At the extreme end of the pencil is the actuating end piece 5 which is formed, in the pencil illustrated, as a cylindrical cap having an end partition 5^a positioned against the rear face 2^b of the cap 2. The outer end of the cylinder 5 is turned inward or otherwise suitably provided with some gripping surface as indicated at 5^b to engage and hold an eraser. The partition 5^a is provided with a central opening to be in alignment with and correspond to the opening 2^c in the cap 2 for the reception of the rear end of the actuating screw and the securing of an end between the plates 5^d and in the space 5^d as will be described.

A central partition 6 is securely fixed within the barrel by brazing, soldering or suitable means, and divides the inner bore of the barrel into a front and rear chamber, the front chamber being a magazine for extra leads, and the rear chamber containing the actuating screws. The partition 6 has an axial opening 6^a for the reception of the guide tube as will be described.

The guide tube 7 is also rigidly mounted within the opening 6^a of the partition 6 by brazing or soldering, and is thus fixed with respect to the barrel. The tube 7 has the extreme front end 7^a projecting beyond the end of the barrel and adapted to engage the inclined wall 3^b of the tip. The rear portion of the tube on the opposite side of the partition 6 is indicated at 7^b and is provided with a slot through the wall thereof at 7^c, this slot extending from the rear end of the guide tube substantially all of the way to the partition.

The actuating helically coiled spring screw member 8 substantially fills the diameter of the bore of the barrel and extends the full length of the rear chamber. It will be noted that the member 8 is free to revolve within the circular walls of the barrel; that the lateral portions of the spring 8 are loosely positioned within the barrel, and that the coils or turns of the member 8 are positioned apart a distance substantially as great as the cross section of the material of the spring. The extreme rear end 8^a of the member 8 extends through the opening 2^c and is bent at right-angles to the longitudinal axis of the spring 8 and fixed within the actuating end piece 5 by

being soldered, brazed, or otherwise secured between the plates 5^d, which latter provide the space 5^d having a width substantially the same as the width of the end 8^a. In Fig. 1 the end 8^a is illustrated as being continued through the opening 2^c by an extension portion 8^b, which latter is necessarily positioned axially. The opposite end of the member 8 or the front end thereof is indicated at 8^c, which end normally should be located relatively close to the partition 6 so that the partition would prevent the actuated screw from becoming unfastened from the coils of the screw 8.

The combined actuated screw and plunger 9 is illustrated in its removed position in Fig. 2 and in its assembled position with the other parts in Fig. 1. This structure is peculiar in that the plunger rod is continuous and formed in one piece with the actuated screw portion 9^a. The member is inserted in the rear end of the barrel, when the cap 2 and actuating piece 5 with the actuating screw are removed, by fitting the rod 9 into the slotted guide tube 7. A right-angle shoulder 9^b extends from the straight rod 9 to the helical turn of the actuated screw part 9^a, this portion 9^b being illustrated in Fig. 3. The right-angle shoulder 9^b extends through the open slot 7^c and is prevented from turning by the walls of this slotted opening. Comparing the respective size and pitch of the turns of the helical screw portions 8 and 9^a as shown in Figs. 1 and 2, it will be noted that these dimensions are substantially the same as may be compared by observing the distance A—B in Fig. 1 with the distance C—D in Fig. 2. Referring to Fig. 1 it will be noted that the turn of the member 9^a substantially fills the space between the adjacent turns of the member 8.

The structure is assembled by first inserting a combined plunger 9 and actuated screw 9^a within the slotted tube so that the shoulder 9^b extends through the slot. The rear cap 2 is then screwed into place by bringing the end 8^c of the actuating screw into screw threaded engagement with the coils 9^a and completing this turning movement until the end 8^c is moved to its extreme position near the partition 6. The rear cap 2 is screwed into position on the threads 1^c and soldered or brazed to prevent turning. The screw threaded portion may be so formed that the binding of the threads serves to hold the cap 2 from turning with respect to the barrel. The actuating end piece 5 may then be turned with respect to the cap 2 in order to adjust the position of the plunger 9 within the guide tube 7. Leads are normally inserted by removing the front end cover 3 and slipping each additional lead as used into the front end of the tube 7, and then replacing the cap 3.

Adjustment of the member 5 draws the plunger forward or backward, and the lead is forced from the guide tube 7 through the bore 3^t into position for use at the tip 5 of the pencil 3^e.

The arrangement of the working parts provides a resilient springlike yielding movement to the lead which is most desirable in making for easy writing. The simplicity of the parts has provided an inexpensive construction and one which is not subject to breakage or repeated adjustments. The materials may be made from substantially any readily worked metal, and the substitution of one material over another will not depart from the scope of this invention.

I claim:

1. In a pencil, the combination of a barrel, an actuating end piece at one end of said barrel, an actuating helically coiled spring screw member rotatably mounted within said barrel and having one end thereof fixed to said actuating end piece, the coils 20 of said spring member substantially filling the bore of said barrel and being free to turn therein, and having adjacent coils spaced apart, and a unitary combined reciprocating plunger and screw within said barrel, and having as one portion thereof a straight rod and as another portion an actuated helical screw member slidably mounted within said barrel for longitudinal movement, the coils of said actuated member being substantially of the same curvature and pitch as the actuating spring member and fitting between adjacent turns of the same.

2. In a pencil, the combination of a barrel, an actuating end piece at one end of said barrel, an actuating helically coiled spring screw member rotatably mounted within said barrel and having one end thereof fixed to said actuating end piece, the coils of said spring member substantially filling the bore 40 of said barrel and being free to turn therein, and having adjacent coils spaced apart, and a unitary combined reciprocating plunger and screw within said barrel, and having as one portion thereof a straight rod and as another portion an actuated helical screw member slidably mounted within said barrel for longitudinal movement, the coils of said actuated member being substantially of the same curvature and pitch as the actuating 45 spring member and fitting between adjacent turns of the same, said straight rod being positioned axially and centrally with respect to the helix of said actuated screw member.

3. In a pencil, the combination of a barrel, an actuating end piece at one end of said barrel, an actuating helically coiled spring screw member rotatably mounted within said barrel and having one end thereof fixed to said actuating end piece, the coils of said 60 spring member substantially filling the bore

of said barrel and being free to turn therein, and having adjacent coils spaced apart, and a unitary combined reciprocating plunger and screw within said barrel, and having as one portion thereof a straight rod and as another portion an actuated helical screw member slidably mounted within said barrel for longitudinal movement, the coils of said actuated member being substantially of the same curvature and pitch as the actuating 70 spring member and fitting between adjacent turns of the same, said straight rod being positioned axially and centrally with respect to the helix of said actuated screw member, and having one end continued substantially at right-angles to said actuated screw member and rigidly fixed with respect thereto.

4. In a pencil, the combination of a barrel, an actuating end piece at one end of said barrel, an actuating helically coiled spring screw member rotatably mounted within said barrel and having one end thereof fixed to said actuating end piece, the coils of said spring member substantially filling the bore 80 of said barrel and being free to turn therein, and having adjacent coils spaced apart, a fixed tube centrally mounted within said barrel and having a rear portion thereof extending within said actuating spring and 85 slotted for a substantial portion of its length within said actuating spring, and a unitary combined reciprocating plunger and screw within said barrel, and having as one portion thereof a straight rod and as another portion an actuated helical screw member slidably mounted within said barrel for longitudinal movement, the coils of said actuated member being substantially of the same curvature and pitch as the actuating spring member 90 and fitting between adjacent turns of the same.

5. In a pencil, the combination of a barrel, an actuating end piece at one end of said barrel, an actuating helically coiled spring screw member rotatably mounted within said barrel and having one end thereof fixed to said actuating end piece, the coils of said spring member substantially filling the bore 100 of said barrel and being free to turn therein, and having adjacent coils spaced apart, a barrel cap mounted on the end of said barrel and positioned between said actuating end piece and said actuating spring, and having a central opening therethrough, and an extension from the spring extending radially to a point opposite said opening and thence axially through said opening, said extension being rigidly secured to said actuating end piece.

6. In a pencil, the combination of a barrel having the bore thereof divided transversely by a partition into two main chambers consisting of a rear chamber and a forward chamber, and an actuating end piece at the 110 115 120 125

rear end of said barrel, a guide tube extending centrally the length of said forward chamber and through said partition and projecting centrally into said rear chamber, 5 the portion of said tube in said rear chamber being provided with a longitudinally extending slot through the wall thereof, an actuating helically coiled spring screw member rotatably mounted within said rear chamber and encircling said slotted tube, and a unitary combined reciprocating plunger and actuated screw within said barrel having as one portion thereof, a straight rod mounted within said guide tube, and as 15 another portion, an actuated helical screw member encircling the slotted portion of said tube, the coils of said actuated member being substantially of the same curvature and pitch as the actuating spring member 20 and fitting between adjacent turns of the same.

7. In a pencil, the combination of a barrel having the bore thereof divided transversely by a partition into two main chambers consisting of a rear chamber and a forward chamber, an actuating end piece at the rear end of said barrel, a barrel rear end cap detachably mounted on said barrel between said actuating end piece and said barrel, a 25

guide tube extending centrally the length 30 of said forward chamber and through said partition and projecting centrally into said rear chamber, the portion of said tube in said rear chamber being provided with a longitudinally extending slot through the wall thereof, the space in said forward chamber around said guide tube constituting a magazine for extra leads, a barrel forward end cover and pencil tip having a central bore, the walls of which are in alignment 35 with the bore of said guide tube, an actuating helically coiled spring screw member rotatably mounted within said rear chamber and encircling said slotted tube, and a unitary combined reciprocating 40 plunger and actuated screw within said barrel having as one portion thereof, a straight rod mounted within said guide tube, and as another portion, an actuated helical screw member encircling the slotted portion of 45 said tube, the coils of said actuated member being of substantially the same curvature and pitch as the actuating spring member and fitting between adjacent turns of the same. 50

55 In testimony whereof I affix my signature.

FRANCIS W. D'OLIER.
